(57) CLAIM

The ornamental design for a divided savings bank, as shown and described.

DESCRIPTION

FIG. 1 is a perspective view of a divided savings bank incorporating my new design, showing the lid in closed position;

FIG. 2 is a front elevational view thereof, the broken line showing of the vertical dividers is for illustrative purposes only and forms no part of the claimed design;

FIG. 3 is a right side view thereof, the left side being a mirror image of that shown;

FIG. 4 is a rear elevational view thereof, the broken line showing of the vertical dividers is for illustrative purposes and forms no part of the claimed design;

FIG. 5 is a top plan view thereof, the broken line showing of the vertical dividers is for illustrative purposes only and forms no part of the claimed design; and,

FIG. 6 is a perspective view similar to FIG. 1, showing the lid in open position.
